(57) **CLAIM**

The ornamental design for a centrifuge housing, as shown and described.

DESCRIPTION

FIG. 1 is a perspective view, taken from the left side and front, of a centrifuge housing according to my novel design; FIG. 2 is a perspective view, taken from the right side and rear, thereof;

FIG. 3 is a front view thereof;

FIG. 4 is a left side view thereof;

FIG. 5 is a rear view thereof;

FIG. 6 is a top view thereof; and,

FIG. 7 is a bottom view thereof.

The broken lines are for illustrative purposes only and form no part of the claimed design.
